UNITED STATES PATENT OFFICE

EDWIN T. HALL, OF BOSTON, MASSACHUSETTS, ASSIGNOR TO SULLIVAN MACHINERY COMPANY, A CORPORATION OF MASSACHUSETTS

DRILLING MECHANISM

Application filed March 30, 1926. Serial No. 98,599.

This invention relates to drilling mechanisms and more particularly to rock drilling mechanisms of the fluid pressure actuated percussive type.

5 In modern quarrying it is the usual practice to drill a series of aligned holes in the rock by means of a hammer drill mounted on a usual quarry bar. After the holes are drilled a broaching tool is substituted for the 10 drilling tool and the partitions between the holes are broached or cut away, thereby producing a continuous cut or channel in the rock. The desired section or block of the rock is then split away in a well known 15 manner.

The main object of this invention is to provide an improved drilling mechanism whereby a plurality of holes may be simultaneously drilled in the rock, thereby substantially decreasing the time consumed in separating a section of the rock from its natural bed. Another object of this invention is to provide an improved drill mounting whereby a plurality of unitary drilling tools may 20 be mounted on a common support in an improved and simplified manner. Another object of this invention is to provide improved guiding means for the cutting tools during the starting or "spotting" of a hole. These 25 and other objects of this invention will, however, hereinafter more fully appear.

This invention in one of its preferred embodiments may comprise a pair of unitary percussive rock drilling tools having a common control and fluid supply connection and these drilling tools be secured in an improved manner on a common support or cradle, the latter being slidably mounted in a guiding frame. Means may be provided for simultaneously feeding the drills and cradle relative 35 to the guiding frame and such means preferably comprises a rotatable feed screw carried by the guiding frame and cooperating with a stationary feed nut carried by the drill 40 cradle. Improved means are also provided for guiding the cutting tools of the drills and such means include a guiding member secured to the guiding frame and having portions embracing both of the cutting tools.

50 In the accompanying drawings there is

shown for purposes of illustration one form which my invention may assume in practice, together with certain modifications.

In these drawings,

Fig. 1 is a plan view of the improved drilling mechanism, parts being broken away to facilitate illustration. 55

Fig. 2 is a central longitudinal sectional view taken substantially on line 2—2 of Fig. 1.

Fig. 3 is an end view of the mechanism 60 shown in Fig. 1.

Fig. 4 is a transverse vertical sectional view taken substantially on line 4—4 of Fig 65 2, the drilling tools being omitted to facilitate illustration.

Fig. 5 is a detail transverse horizontal sectional view taken substantially on line 5—5 of Fig. 3.

Fig. 6 is a detail transverse vertical sectional view taken substantially on line 6—6 70 of Fig. 1, illustrating the guiding means for the cutting tools.

Figs. 7 and 8 are detail views illustrating two modifications of the guiding means for the cutting tools. 75

In the illustrative embodiment of the invention shown in Figs. 1 to 6 there is provided a pair of unitary drilling tools generally designated 1 and 2 of identical structure which are suitably secured to a cradle 3 slidably mounted on a guiding frame or shell 4. The drilling tools 1 and 2 are herein of the fluid pressure actuated percussive type each of which has a cylinder 5 within which a hammer piston, not shown, is reciprocable, 80 this hammer piston being adapted to percussively actuate a drill steel 6 loosely supported within the forward end of the drilling tool in a usual manner. Fluid pressure is adapted to be supplied to the cylinders 5 through a supply line 7, the latter being threaded connected, as at 8 (see Fig. 5) within a manifold member 9 secured as by screws 10 to the rear cylinder heads 11. Fluid pressure is adapted to flow from the supply line 7 through a passage 12 communicating with a usual three way valve 13 rotatably mounted within a bore 14 formed in the member 9. As shown, also communicating with the valve 13 are 85 passages 15 and 16 which communicate 90

through passages formed in the rear heads 11 with usual valve mechanisms 16^a, the latter including a usual automatic valve which distributes the fluid to and from the motor cylinders in a well known manner. As the specific internal structure of these drilling tools does not enter into this invention, further detailed description and illustration of the same is deemed unnecessary. It will be evident that the three way valve 13 is adapted to selectively or simultaneously supply pressure fluid to the cylinders of the drilling tools, a controlling lever 17 being suitably secured to the valve to permit manipulation thereof. In accordance with this invention, the drilling tools 1 and 2 are disposed on their sides with their bottom surfaces adjacent each other and disposed in a vertical plane, the cylinders 5 of these drilling tools having formed thereon lateral guiding members or gibs 18 which are disposable at their opposite ends in recesses 19 and 20 formed within the end portions of the cradle member 3. To prevent displacement of the gibs 18 from these recesses 19 and 20 there is provided a detachable cap member 21 suitably secured, as by screws 22, to the upper surface of the cradle 3 and this cap member has formed therein a longitudinally extending recess or slot 23 and the sides of this member 21 are adapted to embrace the upper portions of the gibs to secure the drilling tools in operative position on the cradle. A screw 24 carried by the member 9 is also provided which threadedly engages the cradle 3, as at 25, and this screw 24 cooperates in the holding of the drilling tools in position on the cradle. From the foregoing description it is evident that upon the removal of the cap member 21 and the screw 24 the drilling tools 1 and 2 may be lifted bodily from the cradle 3, thereby greatly facilitating the dismantling of the machine in case of breakage or wear of the parts thereof. As illustrated, formed on the lower portion of the cradle member 3 are laterally projecting gibs or guiding members 26 (see Fig. 4) which are slidably mounted in guideways 27 formed integral with and extending longitudinally of the guiding frame 4. To effect the feeding of the cradle member and consequently the drilling tools relative to the guiding frame 4 there is provided a rotatable feed screw 28 journaled at its rear end within a yoke member 29 supported on the guiding frame 4 by means of spacers 30 and side rods 31. The forward end of the feed screw 28 is rotatably mounted within a bearing member 32 likewise secured in position on the guiding frame 4 by the side rods 31. In this instance, the rear end of the feed screw 28 has suitably secured thereto an operating crank 33 by means of which the operator may rotate the feed screw. Threadedly connected to the feed screw 28 is a non-ro-

tatable feed nut 34 suitably rigidly held within a bore 35 formed in a depending boss 36 formed integral with the cradle member 3. Formed integral with the guiding frame 4 is a supporting member 37 by means of which the drilling mechanism may be clamped in operative position on a column or quarry bar in a well known manner. In accordance with this invention improved means are provided for guiding the drill steel 6 during the starting or "spotting" of a hole and such means comprises an elongated supporting member 38 having a rectangular end portion 39 which is adapted to fit in a polygonal socket 40 formed within the member 32. The member 38 projects forwardly from the forward end of the guiding frame 4 and has secured, as by bolts 41, at its outer end a member 42 which has laterally projecting bent portions 43 which are adapted to embrace and guide the drill steels 6.

In the modified form of guiding means shown in Fig. 7, there is provided guiding means for the drill steels 6 which is operative when the mechanism shown in Fig. 1 is turned on its side, the drill steels being in a superimposed position at that time. In this instance, the elongated supporting member 38 has secured thereto at its forward end as by bolts 44 a vertically disposed member 45 having formed thereon at its upper and lower ends laterally projecting bent portions 46 which embrace and guide the drill steels 6. In the modified form of guiding structure shown in Fig. 8 there is also shown a projecting portion 47 formed integral with the bearing member 32 and the outer end of this portion 47 has pivoted thereon, as at 48, an elongated supporting member 49 which has secured thereto at its outer end, as by bolts 50, the drill steel embracing and guiding means 51 which is similar to the guiding member 42 as shown in Fig. 6. Formed on the member 49 and projecting rearwardly from the pivot 48 is an arm 52 through which and the portion 47 a pin 53 is adapted to project and this pin locks the member 49 in its operative position as clearly shown in full lines in Fig. 8. When it is desired to remove the drill steels 6 from the drilling tools, the pin 53 may be removed and the member 49 swung downwardly to the position indicated by dotted lines in Fig. 8, thereby removing the embracing or guiding portions of the member 51 from adjacent the drill steels 6.

The operation of this improved drilling mechanism is as follows. After the drilling mechanism has been suitably mounted upon a column or quarry member and the cutting ends or bits of the drill steels 6 are suitably positioned relative to the work, it being understood that the drilling tools are in their retracted positions in the guiding frame 4, the operator suitably manipulates the valve 13, thereby supplying pressure fluid to the

valve mechanisms 16^a of the drilling tools 1 and 2 and the hammer pistons are consequently reciprocated in their cylinders and thereby impart blows to the shanks of the drill steels 6. The operator then suitably manipulates the lever 33, thereby effecting rotation of the feed screw 28 and consequently feeding the cradle and the drilling tools forwardly within the guiding frame. As the holes are deepened by the cutting bits it is evident that the operator may feed the drilling tools forwardly to maintain the cutting bits at all times adjacent the work. It is obvious that the guiding portions 43 prevent the drill steels from becoming out of alignment during the "spotting" of the holes.

As a result of this invention, it will be noted that an improved drilling mechanism is provided wherein a plurality of holes may be simultaneously drilled and such mechanism is mounted upon a common support or guiding frame. It will also be noted that the unitary drilling tools are mounted on the guiding frame in an improved and simplified manner, it being possible to detach the drilling tools from the supporting cradle with facility. It will further be noted that improved and simplified guiding means are provided for the drill steels during the starting or "spotting" of the holes. These and other advantages of this invention will be clearly apparent to those skilled in the art.

While I have in this application specifically described several embodiments which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a drilling mechanism, a plurality of unitary drilling tools each having gibs secured thereto at the bottom thereof, a cradle having means cooperating with said gibs for maintaining said tools in juxtaposition with their bottoms parallel to a vertical plane and immediately adjacent each other, a guiding frame on which said cradle is slidably mounted, and means for feeding said cradle relative to said guiding frame.

2. In a drilling mechanism, a plurality of unitary drilling tools each having gibs secured thereto at the bottom thereof, a cradle having means including longitudinally extending recesses and a cooperating clamp longitudinally extending with said gibs for maintaining said tools in juxtaposition with their bottoms parallel to a vertical plane and immediately adjacent each other, a guiding frame on which said frame is slidably mounted, and means for feeding said cradle relative to said guiding frame.

3. In a drilling mechanism, a plurality of unitary fluid actuated drilling tools of like construction, a common fluid conducting member rigidly connected to said tools, and a common valve for controlling fluid flow through said member to both tools, a cradle on which said tools are mounted in juxtaposition, a guiding frame on which said cradle is slidably mounted, and means for feeding said cradle and tools simultaneously relative to said guiding frame. 70 75

4. In a drilling mechanism, a pair of unitary fluid actuated drilling tools of like construction, a fluid conducting member rigidly connected to both tools, and a common valve in said member for controlling fluid flow through said member to both tools, a cradle on which said tools are mounted in juxtaposition, said fluid conducting member being rigidly secured to said cradle, a guiding frame 80 on which said cradle is slidably mounted, and means for feeding said cradle and tools simultaneously relative to said guiding frame. 85

5. In a drilling mechanism, a plurality of unitary drilling tools each having a drill steel, a cradle having means for supporting said tools thereon in immediately adjacent relation, a guiding frame on which said cradle is slidably mounted, means for feeding said cradle relative to said guiding frame, 90 and a single means carried by said frame for guiding all of said drill steels. 95

6. In a drilling mechanism, a pair of unitary drilling tools each having a drill steel, a cradle having means for supporting said tools thereon in immediately adjacent relation, a guiding frame on which said cradle is slidably mounted, means for feeding said cradle relative to said guiding frame, and means carried by said frame for guiding both 100 of said drill steels including a single element projecting forwardly from the front end of said guiding frame and having portions embracing both of said drill steels. 105

7. In a drilling mechanism, a plurality of 110 unitary drills of the percussive type, a cradle to which said tools are secured with their bases closely adjacent one another, means for securing said tools on said cradle including 115 a recess on said cradle for engagement with portions of both of said tools, and means removably connected to said cradle and engaging both of said tools for cooperation with said recesses to hold said drilling tools in 120 position, a guiding frame on which said cradle is slidably mounted and means for feeding said cradle relative to said frame.

8. In a drilling mechanism, a plurality of drilling tools, a mounting for said tools comprising a cradle, a single removable retaining means for securing both of said drilling tools directly to said cradle with the bases of said tools vertically disposed adjacent one another, 125 a guiding frame on which said cradle is slid- 130

ably mounted, and means for feeding said cradle relative to said frame.

9. In a drilling mechanism, a pair of separable unitary drilling tools of the percussive type, a cradle, means for securing each of said tools in direct engagement with said cradle, including a single removable clamping means engaging both of said tools, the bases of the tools being disposed in substantially abutting relation in the longitudinal center of the mechanism, a guiding frame on which said cradle is mounted, and means for feeding said cradle relative to said guiding frame.

10. In a drilling mechanism, a pair of unitary drilling tools, a cradle, means for securing said tools with their bases together on said cradle comprising recesses in the cradle each of which receives portions of both of said

20 tools therein, and clamping means engaging other portions of said tools and connected to said cradle for holding said tools in engagement with the recesses and maintaining the bases of said tools in substantially abutting relation, a guiding frame on which said cradle and tools are movably supported, and means for feeding said cradle and tools relative to said support.

11. In a drilling mechanism, a plurality of 30 unitary drilling tools, a cradle, clamping means common to both of said tools for clamping the bases of said tools substantially together in immediately adjacent relation and securing them on the cradle, a guiding frame 35 on which the cradle is slidably mounted, and means for simultaneously feeding the tools relative to the guiding frame.

12. In a drilling mechanism, a plurality of unitary drilling tools of the fluid actuated 40 percussive type each provided with its own distributing valve, a fluid conducting member connected to each of said tools and providing a common fluid supply to all of said distributing valves, a single means for controlling the flow of fluid to all said valves, a cradle, means for detachably securing said fluid conducting member directly to said cradle, a guiding frame to which said cradle is slidably connected, and means for feeding 45 said tools in unison relative to said frame.

13. A mounting for a plurality of rock drills, comprising in combination with cylinders having lateral projections, a carriage, bearings on the carriage to support the 55 drills, and a common clamping means pressing on the projections to hold the drills against movement with respect to the carriage.

14. In a drilling mechanism, a plurality of unitary drilling tools each being of the drifter type and having longitudinally extending gibs or guides adapted to cooperate with guideways on a shell when used as separate mounted drills, a common cradle for receiving all of said tools in parallel relation, and clamping means engaging each of said tools

to secure them on said cradle, a guiding frame on which said cradle is slidably mounted, and means for feeding said cradle relative to said frame to feed said tools uniformly to the work.

15. In a drilling mechanism, a plurality of unitary drilling tools each being of the drifter type and having longitudinally extending gibs or guides adapted to cooperate with guideways when used as separate mounted drills, a common cradle for receiving all of said tools in parallel relation with the bottom surfaces of said gibs or guides in abutting relation, clamping means engaging the gibs on each of said tools to secure them on said cradle, a guiding frame, and means for feeding said cradle relative to said guiding frame to feed said drilling tools uniformly to the work.

16. In a drilling mechanism, a plurality of unitary drilling tools each being of the drifter type and having longitudinally extending gibs or guides adapted to cooperate with guideways on a shell when used as separate mounted drills, a cradle to which said tools are secured with said gibs arranged in parallel relation and directly opposite each other, clamping means engaging each of said tools to secure them on said cradle, a fluid conducting member rigidly connected to both tools, and a common valve for controlling fluid flow through said member to both tools, a guiding frame on which said cradle is slidably mounted, and means for feeding said cradle relative to said guiding frame to feed said drilling tools uniformly to the work.

17. In a drilling mechanism, a plurality of unitary drilling tools each having a drill steel, a cradle having means for supporting said tools in parallel relation thereon, a guiding frame on which said cradle is slidably mounted, means for feeding said cradle relative to said guiding frame to feed said drill steels uniformly into the work, and a single drill steel guiding means carried by said frame for guiding all of said drill steels.

18. In a drilling mechanism, a pair of unitary drilling tools each having a drill steel, a cradle for supporting said tools in parallel relation thereon, a guiding frame on which said cradle is slidably mounted, means for feeding said cradle relative to said guiding frame to feed the drill steels uniformly into the work, means carried by said guiding frame for guiding both of said drill steels including an element rigidly connected to the guiding frame, a member pivotally connected to said element and having means for embracing both of said drill steels, and retaining means for holding said pivoted member in operative position.

19. In a drilling mechanism, a pair of unitary drilling tools each having a drill steel, a cradle having means for supporting said tools in parallel relation thereon, a guiding

frame on which said cradle is slidably mounted, means for feeding said cradle relative to said guiding frame to feed said drill steels uniformly into the work, a single drill steel 5 guiding means carried by said frame and extending materially beyond the end of the frame comprising a member rigidly connected to the guiding frame, a second member connected to said first member and carrying 10 guide means embracing both of said drill steels, said second member being swingable relative to said first member to permit removal of the drill steels, and means for retaining said members in fixed relation to 15 hold said guides in operative position.

In testimony whereof I affix my signature.
EDWIN T. HALL.

CERTIFICATE OF CORRECTION.

Patent No. 1,761,337.

Granted June 3, 1930, to

EDWIN T. HALL.

It is hereby certified that error appears in the printed specification of the above numbered patent requiring correction as follows: Page 1, line 3, for the misspelled word "actauted" read "actuated"; page 3, lines 58 and 59, claim 2, for "cooperating clamp longitudinally extending" read "longitudinally extending clamp cooperating"; and that the said Letters Patent should be read with these corrections therein that the same may conform to the record of the case in the Patent Office.

Signed and sealed this 22nd day of July, A. D. 1930.

(Seal)

**Wm. A. Kinnan,
Acting Commissioner of Patents.**
